UNITED STATES PATENT OFFICE.

HENRI JEAN JOSEPH MARIE DE REGNAULD DE BELLESCIZE, OF PARIS, FRANCE.

ANTIINTERFERENCE RADIO SIGNALING SYSTEM.

Application filed March 19, 1924, Serial No. 700,246, and in France April 20, 1923.

The present invention relates to a new and improved anti-interference system for radio signalling.

More specifically my invention relates to a system which utilizes the fact that oscillations caused by disturbances in the receiving apparatus present, as compared with the oscillation of the signal, a difference in phase that changes from one disturbance to another. 5
10 By combining conveniently with a local oscillation or wave of a phase that is constant with relation to the wave of the signal, a complex oscillation is set up by virtue of the combined effect of the signal wave and the wave due to atmospherics, and it is found that, by choosing a convenient phase for the local or auxiliary oscillations, the effect of the atmospheric waves upon the indicating device can be diminished in a given 15 proportion with reference to the energy of the signal.

Let us consider the case of a receiving apparatus simultaneously passed by:

A signal: $S \sin(\omega t + \Phi)$

25 A stray oscillation: $P e^{-\alpha t} \sin(\omega t + \psi)$

An auxiliary oscillation: $A \sin(\omega t + \xi)$ of the same frequency as the signal and constantly adjusted with reference to it.

Various objects and advantages of my invention will appear from the following description taken in connection with the accompanying drawing in which,

The figure is a schematic diagram of a preferred embodiment of my invention.

30 The signals of a form $S \sin(\omega t + \phi)$, the frequency of which is preferably lowered by the aid of any convenient means (heterodyne, for instance) act upon the circuit 1 which is connected with tubes 2 and 3. The circuit 35 1 is a low frequency receiving circuit placed beyond the ordinary detector which is not shown. The local source of oscillations acts at some point of the high frequency circuits in front of the detector. Tube 2 transmits the incoming oscillations to resonance circuit 40 7 possessing a high time constant through the intermediary of tube 4 and a coupling 5-6, comprising a variable mutual inductance and a potentiometer device, so that allowance is 45 made for adjusting the phase ξ of the local oscillation of the form $A \sin(\omega t + \xi)$ induced in 7. By convenient adjustment, equality between ϕ and ξ is possible. The signal is 50 integrally recorded, whereas a given stray 55 will be diminished to an extent measured by $\cos(\psi - \xi)$.

The resonator 7, tuned to pulsation of the signal, has a very high time-constant, or in other words, low damping. As a consequence, the signal periodically interrupted by 60 keying is changed in 7 into an unbroken oscillation, consecutive trains corresponding to signal impulses becoming superposed upon one another on account of the high time constant. 7 therefore is the seat of an auxiliary 65 oscillation being more or less continuous and of the same period as the signal. After this result is attained, it becomes necessary to insure phase coincidence by the means 5-6. In other words, the operator is able to impart to the phase ξ of the auxiliary oscillation 70 at 7 any desired value. In doing this, he is guided by the intensity of the signal received at 8, the intensity being of a maximum value for $\phi = \xi$, since $\cos(\phi - \xi) = 1$. 75

The arrangement of 5-6 consists of two coupling devices, the one inductive (transformer with variable coupling,) the other conductive (potentiometer resistance). By this means, as stated above, it is possible to vary 80 the phase of the oscillations applied to the grid of the valve 4 and to give to it any desired value in relation to the phase of the oscillations at the plate of valve 2. The phase of these oscillations can then be adjusted in 85 such a way that after having passed the resonator 7 they will reinforce the signal oscillations coming directly from circuit 1 to valve 3. Since all parasitic oscillations 90 whether damped or not will have some phase (which is moreover variable if the oscillations are damped) and this phase will in almost every case be different from that of the signal, the beats due to the heterodyne and the parasite will not be reinforced by the current derived from circuits 2, 5, 6, 4, 7. The 95 oscillation of the form $A \sin(\omega t + \xi)$ is the local oscillation produced by the passage of part of the current coming from the resonator 1 through the assemblage 2, 5, 6, 4, 7, and not by a separate source. This oscillation has naturally the same oscillation as the signal. The local oscillation is therefore, as has just been shown, different from that of the heterodyne employed to lower the frequency. The high frequency current is first combined with the heterodyne and rectified in apparatus which are not shown in the drawing because they are well known. This 100 signal current, modulated by the heterodyne and rectified, then arrives at the resonator 1 shown in the drawing. On issuing therefrom 105 110

it is divided into two parts of which the one is fed directly to the valve 3 without change while the other is by the assemblage 2, 5, 6, 4, 7, adjusted in phase and transformed into a 5 quasi stationary oscillation. The phase of the oscillation fed directly from 1-3 is ϕ while the phase adjusted in 5-6 of the oscillations transmitted by the shunt circuit is ξ . The resultant phase acting on the valve 10 3 is $\phi - \xi$. Therefore the continuous current in the plate circuit of valve 3 and in the indicator 8 is proportional to $S \cos(\phi - \xi)$. By suitable adjustment of the elements 5 and 6 the current becomes proportional to the signal 15 strength when $\phi = \xi$.

Having described my invention, what I claim is:

1. In radio signalling, the method of minimizing the effects of disturbing oscillations 20 on the signalling oscillation, which comprises diverting a portion of the signalling oscillations for producing an auxiliary oscillation of the same frequency as the signalling oscillations and adjusting the phase of said auxiliary oscillation with respect to that of the 25 signalling oscillations whereby the disturbing oscillations are weakened with reference to the signal oscillations.

2. In radio signalling, the method of minimizing the effects of disturbing oscillations 30 on the signalling oscillations, which comprises diverting a portion of the signalling oscillations for producing an auxiliary oscillation of the same frequency as the signalling 35 oscillations, adjusting the phase of said auxiliary oscillation with respect to that of the signalling oscillations, and recombining the diverted portion with the signalling oscillations, whereby the disturbing oscillations are 40 weakened with reference to the signal oscillations.

3. In radio signaling, the method of minimizing the effects of disturbing oscillations 45 on the signaling oscillations which comprises combining the incoming energy with oscillations derived therefrom of the same frequency as the signaling oscillations and adjusting the phase thereof to strengthen the signaling 50 oscillations relative to the disturbing oscillations.

4. A device for receiving signalling oscillations and reducing the effects of disturbing waves comprising means responsive to the received energy and means for applying oscillations of the same frequency as the signaling oscillations to said first named means, said last named means comprising means for adjusting the phase of the applied oscillations for reinforcing the signaling oscillations.

60 5. A device for receiving signaling oscillations and reducing the effects of disturbing oscillations comprising a main circuit including signal responsive means and an auxiliary circuit connected to said signal responsive means and to said main circuit adapted to

derive energy from the incoming signaling oscillations and including means for adjusting the phase of the oscillations therein for reinforcing the signaling oscillations.

6. A device for receiving signaling oscillations and reducing the effects of disturbing waves comprising a resonant circuit, a vacuum tube connected therewith and a signal responsive device connected to said vacuum tube, an auxiliary circuit connected to said resonant circuit and to said signal responsive device adapted to derive energy from the incoming signalling oscillations and comprising means for adjusting the phase relationship of the oscillations therein with respect 70 to the signalling oscillations to obtain maximum intensity, said auxiliary circuit including a portion having a high time constant.

7. A device for receiving signaling oscillations and reducing the effects of disturbing oscillations including a resonant circuit, a vacuum tube connected to said circuit and signal responsive means connected to said vacuum tube, an auxiliary circuit connected to said signal responsive means including two 85 vacuum tubes connected in cascade to said resonant circuit adapted to derive energy from the incoming signal oscillations and said circuit comprising means for adjusting the phase relationship of the oscillations in said 90 vacuum tubes whereby they will reinforce the signaling oscillations, said circuit also comprising a portion having a high time constant.

8. A circuit arrangement for receiving signalling oscillations and reducing the effects of disturbing oscillations, comprising a main circuit for receiving a major portion of the incoming energy, a shunt circuit comprising means for diverting a portion of the incoming energy, phase adjusting means connected with said shunt circuit for insuring phase coincidence between the diverted portion of the incoming energy and the main portion, and means for recombining both of said portions, whereby the signalling oscillations are 100 reinforced and the disturbing oscillations weakened.

9. In radio signalling, the method of minimizing the effects of disturbing oscillations 115 on the signalling wave which comprises diverting a portion of the signalling wave for producing an auxiliary oscillation of the same frequency as the signalling wave, rejecting the disturbing oscillations within a circuit 120 having a high time constant, adjusting the phase of said auxiliary oscillation with respect to that of the signalling wave, and recombining the diverted portion with the signalling wave whereby the disturbing oscillations are 125 weakened relative to the signal wave.
